(57) **CLAIM**

The ornamental design for a pregnancy prone positioner, as shown and described.

DESCRIPTION

FIG. 1 is a perspective view of a pregnancy prone positioner showing my new design;

FIG. 2 is a left side elevation thereof, the right side being a mirror image;

FIG. 3 is a front elevation thereof;

FIG. 4 is a top plan view thereof;

FIG. 5 is a bottom plan view thereof; and,

FIG. 6 is a back elevation thereof.

The auxiliary support cushions shown in broken lines in FIGS. 1-4 and 6 are not part of the claimed design.
